UNITED STATES PATENT OFFICE.

HONOR L. EAGER, OF BROOKLYN, NEW YORK.

DEVICE FOR REMOVING FACIAL WRINKLES.

1,319,054.

Specification of Letters Patent.

Patented Oct. 21, 1919.

Application filed March 22, 1919. Serial No. 284,330.

To all whom it may concern:

Be it known that I, HONOR L. EAGER, a citizen of the United States, residing at Brooklyn, in the county of Kings and State 5 of New York, have invented certain new and useful Improvements in Devices for Removing Facial Wrinkles, of which the following is a specification.

This invention relates to a device for removing facial wrinkles and is adapted to accomplish this result with a minimum of discomfort to the user.

Considerable annoyance has accompanied the use of devices of this general character 15 heretofore known, owing to the fact that they contact constantly with the head of the wearer, causing chafing and irritation of the scalp, or they are provided with adhesive members for attachment to the skin 20 of the face, and, in consequence, are apt to defeat the very object for which they are designed by preventing face circulation of blood in the tissues under the skin which latter is necessary to such contour as to completely fill out the skin and remove wrinkles 25 and flabbiness.

The object of this invention is to provide a device for removing facial wrinkles and double-chin and other blemishes due to depletion 30 of the face tissues which causes looseness of the skin, and to make the device comfortable to wear and non-injurious to the health of the wearer or to the parts with which it comes in contact.

35 This purpose I accomplish by constructing the device in such manner that it will not contact with the head and face of the wearer except at the points of grip upon the facial skin.

40 Furthermore, I provide a device which may be worn under and concealed by the hair of the wearer, thus permitting it to be worn at all times and prevent wrinkles and the like becoming reset in the skin as is 45 common when devices are used which may only be worn in private because of their unsightly appearance.

To this end the invention consists in a 50 resilient band or strip of metal, or other suitable material having the requisite amount of stable resiliency, adapted to partially encircle but not touch the head of the wearer, and provided at its ends with suction or other devices adapted to grip the 55 skin of the face, for example, adjacent the ears, without injury thereto, and having

substantially midway of its length a soft cushion or pad to prevent contact of the band or strip with the head of the wearer, and it consists further in means for adjusting the length of the band or strip to the size of the wearer's head, as I will proceed now to explain and finally claim.

In the accompanying drawings illustrating the invention, in the several figures of 65 which like parts are similarly designated, Figure 1 is a perspective view of the device. Fig. 2 is a section taken through one of the face engaging pads. Fig. 3 is a partial sectional plan view of one of the pads showing the adjusting means. Fig. 4 is a plan view, and Fig. 5 is a section on line 5-5, Fig. 4 of a modification of the pad adjusting means. Fig. 6 is a side view of a woman's head showing wrinkles and other 75 blemishes. Fig. 7 is a side view of the same head showing the device of the invention in position and its effect, and Fig. 8 is a front view of the head showing the manner in which the device is positioned out of contact therewith.

In the form of the invention shown in the drawings, I provide a band or strip 1 of resilient metal or other material suited to the purpose, such as celluloid, hard rubber, 85 or the like, and having attached to it substantially midway of its length a spacing pad or cushion 2 of very soft, pliable material, adapted, when the device is in position for use, to prevent contact of the band or strip 1 with the user's head. The ends of the strip 1 are supplied with recessed pads or cups 3 of any desired form, preferably mounted upon plates 4 having overturned side members 5 which form slide-ways for 90 arms 6 on the ends of the strip 1. By this arrangement the pads may be adjusted longitudinally of the strip and frictionally held thereto in any desired position to accommodate the device to the size of the user's head. 100

In Figs. 4 and 5 I have shown a modification of the adjusting means for the pads or cups 3, comprising a plate 7 having slits 8, the strip 9 formed between the slits being depressed and the arms 6 of the band 1 engaging the plate 7 beneath the side portions 10 thereof, the depressed strip 9 acting as a friction clutching device by engagement with the under side of the ends of the band 1, to hold the pads or cups 3 in proper adjusted position.

In addition to its function as a wrinkle

remover, the device may be utilized for assisting in dressing the hair of the user by wrapping the hair around it in any desired place or otherwise attaching the hair thereto; and it will be apparent that in this connection it is especially useful when false hair is worn.

Although I have shown and described a particular embodiment of the invention it is to be understood that I do not thereby limit myself, as various changes in details of construction and arrangement of parts are permissible within the spirit of the invention and the scope of the following claims.

What I claim is:

1. A device for removing facial wrinkles and the like, comprising a resilient band adapted to partially encircle the human head and face-engaging recessed pads applied to the ends thereof.

2. A device for removing facial wrinkles and the like, comprising a resilient band adapted to partially encircle the human head, and adjustable face-engaging recessed pads applied to the ends thereof. 25

3. A device for removing facial wrinkles and the like, comprising a resilient band adapted to partially encircle the human head and having its free ends provided with extended arm-forming portions, and pad-carrying members having recesses with which said arms are adapted to slidably connect, whereby said members may be adjusted on said resilient band. 30

35 In testimony whereof I affix my signature in presence of two witnesses.

HONOR L. EAGER.
